LOOM BEAM SUPPORT BEARING

William N. Conway, North Grafton, Mass., assignor to
Draper Corporation, Hopedale, Mass., a corporation of
Maine

Filed May 13, 1964, Ser. No. 79,966

Term of patent 14 years

(Cl. D92—15)

FIG. 1.

FIG. 2.

FIG. 3.

FIG. 4.

FIG. 5.

FIG. 6.

FIGURE 1 is a top view of a loom beam support bearing showing my design;

FIGURE 2 is a left side elevational view thereof;

FIGURE 3 is a bottom view thereof;

FIGURE 4 is a right side elevational view thereof;

FIGURE 5 is a rear view thereof;

FIGURE 6 is a front view thereof.

I claim:

The ornamental design for a loom beam support bearing, substantially as shown.
